UNITED STATES PATENT OFFICE

EDWARD C. ALBRIGHT, OF CONNERSVILLE, INDIANA, ASSIGNOR TO INDIANA LAMP CORPORATION, OF CONNERSVILLE, INDIANA, A CORPORATION

LAMP SOCKET AND CONTACT

Application filed November 2, 1928. Serial No. 316,642.

This invention relates to a simplified unitary arrangement for small size lamps.

The chief object of this invention is to simplify the construction and obtain a compact arrangement of the several parts of a lamp construction such as is commonly employed in the automotive industry as side or cowl lights.

One feature of the invention consists in forming the light bulb receiving socket integral with the reflector.

Another feature of the invention consists in the light bulb contact and current conductor connection.

Still a further feature of the invention consists in the mounting of the aforesaid contact upon the reflector and in predetermined relation relative to the bulb socket by a simplified mounting.

The full nature of the invention will be understood from the accompanying drawings and the following description and claims:

In the drawings Fig. 1 is a vertical section through a lamp embodying the invention. Fig. 2 is a rear elevational view of a portion of the reflector and integral light bulb socket. Fig. 3 is a vertical sectional view taken on line 3—3 of Fig. 2 and in the direction of the arrows. Fig. 4 is an elevational view of the combination conductor contact and mounting therefor and is taken in the plane of the offset line 4—4 in Fig. 1 and in the direction of the arrows.

In the drawings 10 indicates a casing having a forward annular shoulder 11 and an inturned flange 12, the shoulder receiving a rim 13 against which it bears. The rim supports a lens closure 14 which bears against an annular sealing strip 15 receivable by an annular flanged seat, the flange being indicated at 16 and the seat at 17, said seat being an extension of a reflector 18. The seat 17 bears against the inturned flange 12 and the entire construction is suitably secured together by any of the arrangements well known in the art. Mounted between the reflector and closure is the usual light bulb 19.

The reflector 18 is centrally apertured as at 20. Punched rearwardly therefrom and

integral therewith there is a pair of tongues 21 oppositely positioned relative to each other, said aperture and tongue being formed to receive the light bulb 19. Each tongue 21 has formed a bayonet slot 22 in registration with the recesses 122 in the reflector to receive the pins 23 carried by the light bulb.

Suitably supported adjacent this socket is a spring contact 26 which engages the light bulb central terminal 27 forming an electrical connection for supplying energy thereto and yieldingly forces the bulb forward in the socket to lock the pins 23 in the bayonet slots.

The contact 26 includes a central anchorage portion 28 and a depending end 29. The central anchorage 28 includes a rectangular slot or hole 30 and at each end, and in alignment with the elongated contact member, the slot is elongated as at 31 and such elongation is formed by angular lugs 32 struck from the body of the contact, said lugs being in alignment and in spaced relation. The reflector 18 is provided with aligned apertures 33 to receive the rivets 34 which extend through insulation plate 35 and thence through aperture 30 of the contact member. The rivets, plate 35, and a complementary plate 36 rigidly mount the contact member in predetermined relation relative to the socket and insulate said contact from the reflector. The plate 36, in addition to being apertured at 37 to receive rivets 34, is notched at each end as at 38. Said notches receive the lugs 32 in interlocking relation. Thus predetermined location of the contact 26 relative to the bulb socket is obtained, and by the aforesaid arrangement all movement between the several parts is eliminated.

The lamp construction includes a bracket 40 for mounting the same and herein it is shown riveted as at 41 to the casing. The casing includes an opening 42. The material is rolled back to form a protecting bead 43. The opening receives the armored cable 44 enclosing the current conducting wire 45. The lower end 29 of the spring contact member is provided with a pair of parallel slots 46 and the portion included therebetween is offset laterally as at 47, the portion immediately therebeneath being oppositely offset lat-

erally as at 48, thereby forming a channel to receive the end 45 of the conductor, which as shown, is turned angularly as at 49. When thus positioned the two portions 47 and 48 5 may be pressed together to anchor the current conducting wire 45 to the spring contact 26.

The invention claimed is:

1. In a lamp having a reflector and a light bulb, the combination of a socket rigid with 10 the reflector and through which the bulb projects, a spring contact terminating adjacent the bulb for contacting therewith and locking it in said socket, said contact being 15 elongated and including a current conductor anchorage at the opposite end and an apertured mid-portion, insulation between the reflector and the contact mid-portion, and means extending through the contact 20 aperture and insulation for supporting the contact upon the reflector in predetermined relation.
2. In a lamp having a reflector and a light bulb the combination of a socket rigid with 25 the reflector and through which the bulb projects, a spring contact terminating adjacent the bulb for contacting therewith and locking it in said socket, said contact being an elongated strap and including an integral 30 current conducting anchorage at the opposite end, and an apertured mid-portion, an insulation plate interposed between said reflector and said contact mid-portion and apertured, another and clamping plate positioned upon 35 the opposite side of said contact mid-portion and clamping means extending through the plates, contact and reflector for clampingly mounting the contact upon the reflector in insulated relation.
3. A device as defined by claim 2 characterized by said contact and one of said plates including an interlocking and locating connection therebetween.
4. A device as defined by claim 2 characterized by the contact mid-portion including 45 a pair of lugs integral therewith and extending angularly thereof and one of said plates including relieved portions for interlocking and locating connection with said lugs.

50 In witness whereof, I have hereunto affixed my signature.

EDWARD C. ALBRIGHT.
